BANK

George W. Harris, New Rochelle, N. Y.

Application March 16, 1950, Serial No. 8,568

Term of patent 3½ years

(Cl. D34—11)

To all whom it may concern:

Be it known that I, George W. Harris, a citizen of the United States, resident of New Rochelle, New York, have invented a new, original, and ornamental Design for a Bank, of which the following is a specification, reference being had to the accompanying drawing, constituting a part hereof:

Fig. 1 is a perspective view of a bank, showing my new design, with gun raised and hand lowered,

Fig. 2 is a perspective view with gun lowered and hand raised,

Fig. 3 is a top plan view of the bank as shown in Fig. 1,

Fig. 4 is a front elevational view thereof,

Fig. 5 is a side elevational view with arm lowered, and

Fig. 6 is a side elevational view with arm raised.

Figs. 3, 4, 5, and 6 are on a reduced scale.

I claim:

The ornamental design for a bank, substantially as shown.

GEORGE W. HARRIS.
